STANHOPE PERKINS, OF FAIRFIELD, ENGLAND.

Letters Patent No. 72,077, dated December 10, 1867. Patented in England, April 4, 1867.

IMPROVED RAILWAY-CROSSINGS.

The Schedule referred to in these Letters Patent and making part of the same.

TO ALL WHOM IT MAY CONCERN:

Be it known that I, STANHOPE PERKINS, of Fairfield, in the county of Lancaster, England, have invented an "Improvement in the Manufacture of Railway-Crossings;" and I do hereby declare that the following is a full and exact description of my said invention.

This invention relates to a novel mode of manufacturing the point or V-rail of railway-crossings, the object being to increase their structural strength. To this end I take a rolled double-headed steel rail, or other section of steel rail, and, having planed off a certain portion of the flanges on one side thereof, I double back the rail upon itself to bring the planed surfaces into contact, and I thus form the nose of the point-rail out of a double thickness of the web of the rail. The side of the rail, at the part where it is to be creased or doubled back, I first indent by a smart blow, and I then set the rail so that the portion of the flanges required to be removed may be cut away by a planing-tool. I next heat the rail in the centre and bend it back, and close the parts on an anvil until the planed surfaces meet with each other. I thus leave the nose of the point or V-rail solid, which is very important, as the blow of the wheel is most felt at that part. I then drill through both of the webs, or parts in contact, and rivet or bolt them together, as the case may be. The outer flanges are cut away at the nose and taperred off for a short distance, in the usual way, to give the proper shape to the point-rail. In the accompanying drawing—

Figure 1 is a plan of the improved crossing complete. W W are the wing-rails, and V is the rail forming the crossing go^u-point. A, B, C, and D are the chairs for sustaining the several parts of the crossing.

Figure 2 is a side view of the crossing complete.

Figure 3 is a longitudinal section of the crossing complete, showing the end of the V-piece in section.

Figure 4 is a transverse section of the crossing immediately in front of the nose of the V-piece, showing in elevation the chair C and the V-piece, and the wing-rails in section.

Figures 5 and 6 are plans of the double-headed rail set and the inside edge planed preliminary to bending. The amount of metal planed off is indicated in both these figures by the red lines.

Figure 7 shows the V-rail bent to a right angle. When the points marked G G (which indicate the limits of the planed surface) are brought together, the rail forms the required angle or V-part of the crossing. The length of the planed surface from G G to nose will vary according to the size of angle or V-point required.

The chairs marked B and C are shown on the drawing as bolted, but they may be secured with wood keys, if preferred.

I would here remark that some of the advantages of crossings made on this plan, are, that they can be readily and economically made by planing or shaping-machines. If made of rolled steel rails they are as durable as cast-steel crossings, and can be supplied at much less cost than any of the patented cast-steel or iron crossings, and they are safer and make a better and more uniform road, and the crossing or V-point can be made to fit the C chair perfectly, and is also reversible.

Having now explained the nature of my invention, I wish it to be understood that I claim—

Forming the points or V-parts of crossings, without splice, by bending the rail, prepared as above described, back upon itself, and securing the abutting parts in the manner and for the purpose above set forth.

In witness whereof, I, the said STANHOPE PERKINS, have hereunto set my hand and seal, this tenth day of August, in the year of our Lord one thousand eight hundred and sixty-seven.

STANHOPE PERKINS. [SEAL.]
